(57) **CLAIM**

The ornamental design for a solar panel, as shown and described.

DESCRIPTION

FIG. 1 is a front perspective view of a first embodiment of a solar panel showing our new design;

FIG. 2 is a rear perspective view of the solar panel of FIG. 1;
FIG. 3 is a front elevational view of the solar panel as seen in FIG. 1;

FIG. 4 is a rear elevational view of the solar panel as seen in FIG. 2;

FIG. 5 is a left-side view of the solar panel as seen in FIG. 2;
FIG. 6 is a right-side view of the solar panel as seen in FIG. 2;
FIG. 7 is a top planar view of the solar panel as seen in FIG. 2;

FIG. 8 is a bottom planar view of the solar panel as seen in FIG. 2;

FIG. 9 is a front perspective view of a second embodiment of a solar panel showing our new design;

FIG. 10 is a rear perspective view of the solar panel of FIG. 9;
FIG. 11 is a front elevational view of the solar panel as seen in FIG. 9;

FIG. 12 is a rear elevational view of the solar panel as seen in FIG. 10;

FIG. 13 is a left-side view of the solar panel as seen in FIG. 10;
FIG. 14 is a right-side view of the solar panel as seen in FIG. 10;

FIG. 15 is a top planar view of the solar panel as seen in FIG. 10; and,

FIG. 16 is a bottom planar view of the solar panel as seen in FIG. 10.

The broken lines shown represent unclaimed subject matter and form no part of the claimed design.

1 Claim, 12 Drawing Sheets
